United States Patent Office.

JACOB STOODY, OF RIPLEY, OHIO.

Letters Patent No. 70,644, dated November 5, 1867.

IMPROVEMENT IN LIFTING-JACK.

The Schedule referred to in these Letters Patent and making part of the same.

TO ALL WHOM IT MAY CONCERN:

Be it known that I, JACOB STOODY, of Ripley, in the county of Brown, and State of Ohio, have invented a new and improved Lifting-Jack; and I do hereby declare that the following is a full, clear, and exact description thereof, which will enable those skilled in the art to make and use the same, reference being had to the accompanying drawings, forming part of this specification.

This invention relates to a new and improved method of constructing jacks for lifting purposes, and the invention consists in operating upon an upright lifting-bar by an eccentric lever, and in the general construction and arrangement of parts, as will hereinafter be described.

Figure 1 represents a longitudinal side or front view of the machine, showing its construction and arrangement.

Figure 2 is an edge view of the same.

Similar letters of reference indicate corresponding parts.

A represents the stand of the jack, which is made of either wood or metal, and of suitable length and size for the purpose intended. B is the lifting-bar, which moves up and down in a groove in the stand, the face of which is flush with the stand up to the shoulder C, against which the eccentric operates. The bar is held in place by a metallic plate, a, on the stand, at its lower part, and by a metallic cap-plate, b, on the top of the stand. The cap-plate projects sufficiently to allow the bar to pass up through a mortise, as seen in the drawing. D is the eccentric, and E is the eccentric lever. F, fig. 2, is an adjustable ratchet-toothed rack, which is hung on a pivot on the stand for the purpose of holding the eccentric in any desired position. The eccentric is hung or pivoted to the stand at the point G, and it will be seen that the motion of the bar B or throw of the eccentric is equal to the distance of the pivot or fulcrum G to any portion of the periphery of the eccentric. When the lever is elevated the bar will be down, and the jack can be placed for operating or lifting.

By depressing the lever the eccentric will gradually raise the bar by traversing the shoulder C. When the desired elevation of the vehicle or article raised has been obtained, the rack F is brought forward and adjusted under the eccentric, as seen in fig. 2, which holds the eccentric, and the weight raised in combination with the fulcrum-pivot G, in the desired position.

This jack is more especially designed for lifting wagons and other vehicles, but may be advantageously applied to other purposes.

Having thus described my invention, I claim as new, and desire to secure by Letters Patent—

The stand A, the bar B, the eccentric D, with lever E, and the rack F, constructed, arranged, and combined substantially as shown for the purposes set forth.

JACOB STOODY.
